DESIGN FOR A BUTTER SERVING MACHINE

Sherman A. Thomas, Rochester, N. Y.

Application October 18, 1940, Serial No. 95,924

Term of patent 14 years

To all whom it may concern:

Be it known that I, Sherman A. Thomas, a citizen of the United States, residing at Rochester, in the county of Monroe and State of New York, have invented a new, original, and ornamental Design for a Butter Serving Machine, of which the following is a specification, reference being had to the accompanying drawing, forming a part thereof.

The dominant features of my design are illustrated in full lines in the figures.

I claim:

The ornamental design for a butter serving machine, as shown and described.

SHERMAN A. THOMAS.
